UNITED STATES PATENT OFFICE.

JOHN HAYES, OF BELLE VERNON, PENNSYLVANIA.

AEROPLANE.

Application filed February 15, 1922. Serial No. 536,725.

To all whom it may concern:

Be it known that I, JOHN HAYES, a citizen of the United States, residing at Belle Vernon, in the county of Fayette and State of Pennsylvania, have invented certain new and useful Improvements in Aeroplanes, of which the following is a specification, reference being had to the accompanying drawings.

10 This invention relates to aeroplanes, and more particularly to a device for use in conjunction with an aeroplane to assist in recovering from nose dives, tail spins and the like.

15 An important object of the invention is to provide a device of this character which readily lends itself to the structure of planes now in common use and which may be readily released by the operator of the plane 20 when so desired.

A further object of the invention is to provide a device of this character which may be inserted between the empennage and body structure of an aeroplane without materially altering the present construction 25 thereof.

Other objects and advantages of the invention will become apparent throughout the course of the following description.

30 In the accompanying drawings wherein for the purpose of illustration is shown a preferred embodiment of my invention and wherein like reference characters designate like parts throughout:

35 Figure 1 is a side elevation of the rear end of the fuselage of an aeroplane constructed in accordance with my invention;

Figure 2 is a plan view thereof;

Figure 3 is a longitudinal vertical sectional view taken therethrough;

Figure 4 is a plan view thereof, parts being broken away;

Figure 5 is a section taken on the line 5-5 of Figure 4;

45 Figure 6 is a section taken on the line 6-6 of Figure 4;

Figure 7 is a section taken on the line 7-7 of Figure 4; and

Figure 8 is a section taken on the line 50 8-8 of Figure 4.

Referring now more particularly to the drawings, the device in the present illustration is in the form of a connecting member 10 disposed intermediate the body proper, 55 as indicated at 11, and the empennage 12 of

the aeroplane, the connecting member being rigidly secured to the body through the medium of longitudinal braces 13 extending through the connecting member and secured to the stabilizer structure 14 of the empennage, as at 15.

Secured to the longitudinal brace members 13 and extending inwardly thereof are members 16 which preferably abut against the forward edge of the stabilizer structure 14.

At the forward end of the connecting member 10 a transverse brace 16^a connects the longitudinal brace members 13 and at each side of the frame adjacent the longitudinal

brace members guides 17 are disposed, having their ends mounted in the support members 16 and in the transverse brace 16^a.

Each of the guide members 17 have slidably mounted thereon a yoke 18. The transverse brace member 16^a has formed therein a rectangular opening in which is secured a longitudinally extending hollow rectangular

guide member 20, the upper and lower members of which are secured to the upper and lower surfaces of the stabilizer structure 14,

50 a spacing member 21 being interposed between one of such upper and lower members and the stabilizer structure for a purpose hereinafter to appear. A yoke 22 is slidably mounted upon the rectangular guide mem-

ber 20.

Secured to the outer face of each of the longitudinal side members 13 is a side member or plate 23, each of the side members being bifurcated at its rear end, as at 24, to permit passage therethrough of the stabilizer structure. The forward ends of the side members 23 extend slightly forwardly

55 of the transverse brace 16^a and have secured thereto a transversely extending baffle member 25 which prevents the passage of air longitudinally of the fuselage into the connecting member 10. Pivottally connected at their rear ends to members 26 secured to the upper

and lower surfaces of the stabilizer structure, as at 27, are upper and lower plane sections 28 and 29 which may hereinafter be referred to as checking planes. These planes

embodiment in their structure longitudinally extending side braces 30 and center braces 31.

100 Each center brace 31 has pivotally connected thereto one end of a link 32, the opposite end of which is pivotally connected to the corresponding side of the yoke 22, and each side

brace 30 has pivotally connected thereto one

105

115

end of a link 33, the opposite end of which is pivotally connected to the corresponding side of its corresponding yoke 18.

The structure of the plane sections 28 and 29 and the structure of the baffle member 25 and body 11 are preferably such as that when the planes are in the position shown in Figure 3, which is their normal position, the stream line effect of the fuselage is not interrupted, the planes being flush with the surface of the baffle member 25 and the baffle member being flush with the surface of the body 11. The plane structures 28 and 29 will, of course, be provided with a suitable fabric covering 34.

Each guide member 17 has secured thereto adjacent the rear end thereof a stop member 35 which limits the movement of its yoke 18 and each yoke 18 has secured thereto at least one spring 36, the opposite end of which is secured to the frame work at some selected point, at present indicated as the support members 26 upon which the plane sections are pivotally mounted. These springs tend to shift the yokes 18 toward the stop members 35 and accordingly, because of the link connections between the yokes and the plane sections, to open the plane sections to the position shown in Figure 1. Normally, movement of these sections is prevented by a latch member 37 mounted upon the baffle member 25 and controlled from an operating lever 38 situated adjacent the operator's seat 39 in the cock pit of the machine, the lever 38 being connected with the latch, as at 40, so that operation of the lever will withdraw the latch. Upon such withdrawal the springs move the planes to the open position where they afford resistance to head motion whether the same be in horizontal flight or in vertical flight such as occurs in a nose dive. These planes will also afford resistance against the movement of the tail which occurs during a tail spin and will materially assist the operator in regaining control of the machine.

The plane sections 28 and 29 may be closed in any desired manner, as manually, after landing. In the present instance, however, I have shown the lower section of the tubular guide member 20 as provided with a slot 41 and the yoke 22 with a lug 42 extending upwardly into the hollow interior of the guide member 20. To this lug 42 is secured a flexible element 43 which extends through an opening 44 formed in the baffle plate 25 and is connected to a pivoted operating lever 45 arranged adjacent the operator's seat. When the planes are in open position, they may, by engaging the operating lever, be closed, the flexible element 43 shifting the yoke longitudinally and moving the planes to the closed position. The planes in closing engage the

latch 37 and withdraw the same against the action of its spring 46 and after the plane has passed the latch is again projected by the spring, locking the same in position. The controls of the empennage may be mounted in any desired manner but because of the opening of the planes it is desirable that none of these controls pass over the planes. They may be mounted either longitudinally and interiorly of the connecting member 10 or to the sides thereof. In the present instance I have shown the baffle plate 25 as provided with a pair of openings 47 aligning with the hollow interior of the guide member 20 and through which extend the steering controls 48. These controls pass longitudinally of the interior of the guide member and to opposite sides of the spacing member 21, thence through openings 49 formed in the support members 26 out upon the empennage structure where they are connected to the tail 50 in any desired manner. The elevator controls 51 are shown as passing to the sides of the connecting member 10 in order that both manners of mounting the controls may be illustrated.

From the foregoing it is believed to be obvious that I have constructed a head motion checking device which is particularly well adapted for use in that it is readily adaptable to the structure of planes at present in common use and in that it may be readily operated. It will furthermore be obvious that the construction as hereinbefore set forth is capable of some change and modification without materially departing from the spirit of my invention and I do not wish to be understood as limiting myself to such structure except as herein-after claimed.

What I claim is:

1. A member disposed intermediate the body and empennage of an aeroplane and embodying plane sections pivoted at their rear ends to said member, means urging the free ends of said sections outwardly from the member, releasable means holding said free ends in engagement with the member, and a baffle plate arranged intermediate the body and said member.

2. A member disposed intermediate the body and empennage of an aeroplane and embodying plane sections pivoted at their rear ends to said member and movable to open and closed positions, said sections when in closed position forming a continuation of the body line of the plane and when in open position affording resistance to head motion of the plane, guides carried by the member intermediate said plane sections, yokes slideable upon the guides, link connections between each of the yokes and each of said plane members, and means urging certain of the yokes in a direction to move the plane sections to the open position.

3. A member disposed intermediate the body and empennage of an aeroplane and embodying plane sections pivoted at their rear ends to said member and movable to 5 open and closed positions, said sections when in closed position forming a continuation of the body line of the plane and when in open position affording resistance to head motion of the plane, guides carried by the member 10 intermediate said plane sections, yokes slideable upon the guides, link connections between each of the yokes and each of said plane members, means urging certain of the yokes in a direction to move the plane sections to the open position, a latch normally holding the plane sections in the closed position, and means for releasing said holding 15 means to permit said sections to assume the open position under the influence of said 20 yokes.
4. A member disposed intermediate the body and empennage of an aeroplane and embodying plane sections pivoted at their rear ends to said member and movable to 25 open and closed positions, said sections when in closed position forming a continuation of the body line of the plane and when in open position affording resistance to head motion of the plane, guides carried by the member 30 intermediate said plane sections, yokes slideable upon the guides, link connections between each of the yokes and each of said plane members, means urging certain of the yokes in a direction to move the plane sections to the open position, latching means normally holding the plane sections in the closed position, means for releasing said 35 holding means to permit said sections to assume the open position under the influence of said yokes, means engaged with one of said yokes for shifting the yokes in a direction opposite to the direction of movement 40 imparted thereto by said urging means, one of said guide members being tubular, and control elements for a shiftable element of the empennage extending longitudinally of 45 said guide.
5. A member disposed intermediate the body and empennage of an aeroplane and embodying plane sections pivoted at their rear ends to said member and movable to 50 open and closed positions, said sections when in closed position forming a continuation of the body line of the plane and when in open position affording resistance to head motion of the plane, guides carried by the member intermediate said plane sections, 55 yokes slideable upon the guides, link connections between each of the yokes and each of said plane members, means urging certain of the yokes in a direction to move the plane sections to the open position, latching means normally holding the plane sections in the closed position, means for releasing said holding means to permit said sections to assume the open position under the influence of said yokes, means engaged with one of said yokes for shifting the yokes in a direction opposite to the direction of movement 60 imparted thereto by said urging means, one of said guide members being tubular, and control elements for a shiftable element of the empennage extending longitudinally of 65 said guide.

In testimony whereof I hereunto affix my signature.

JOHN HAYES.
